(57) **CLAIM**

The ornamental design for a birdwatcher camera as shown and described.

DESCRIPTION

FIG. 1 is a front, left and top perspective view of a birdwatcher camera, showing my design.

FIG. 2 is a rear, right and top perspective view thereof.

FIG. 3 is a rear, right and bottom perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof.

FIG. 10 is an enlarged view of detail 10 in FIG. 1.

FIG. 11 is an enlarged view of detail 11 in FIG. 3.

FIG. 12 is an enlarged view of detail 12 in FIG. 3; and,

FIG. 13 is an enlarged view of detail 13 in FIG. 3.

The broken lines depict portions of the birdwatcher camera that form no part of the claimed design.

(Continued)

The dot-dash broken lines in FIGS. 1, 3, 10, 11, 12 and 13 depict the boundaries of the enlargements that form no part of the claimed design.

1 Claim, 13 Drawing Sheets
